UNITED STATES PATENT OFFICE.

EMILE MADELEINE, OF FLATBUSH, NEW YORK, ASSIGNOR TO PACIFIC MILLS, OF BOSTON, MASSACHUSETTS, A CORPORATION OF MASSACHUSETTS.

DESIGN FOR PRINTED TEXTILE FABRIC.

45,391.

Specification for Design.

Patented Mar. 10, 1914.

Application filed January 20, 1914. Serial No. 813,326. Term of patent 3½ years.

To all whom it may concern:

Be it known that I, EMILE MADELEINE, a citizen of the Republic of France, residing at No. 555 East Seventh street, Flatbush, Long Island, in the State of New York, have invented a new, original, and ornamental Design for Printed Textile Fabrics, of which the following is a specification, reference being had to the accompanying drawing, forming a part thereof.

The figure is a plan view of a portion of a printed textile fabric showing my new design.

I claim:

The ornamental design for a printed textile fabric as shown.

EMILE MADELEINE.

Witnesses:

PHILIP F. WICKSEL,
J. RUDOLPH HEFT.
